COMBINED LOCK AND LATCH

Filed Oct. 15, 1923

2 Sheets-Sheet 3

A technical drawing of a mechanical assembly. At the top, a vertical line labeled '10' extends downwards, ending in a square base labeled '11'. A horizontal line labeled '12' extends to the right from the base. A rectangular frame labeled '20' is positioned above the base. Inside the frame, a central circular area contains a square component labeled '21'. Two vertical springs, labeled '22', are attached to the frame on either side of the central area. A horizontal line labeled '23' extends to the right from the right side of the frame. A vertical line labeled '25' extends upwards from the top of the frame. The entire assembly is mounted on a base labeled '24'.

UNITED STATES PATENT OFFICE.

CHARLES W. RODDY, OF MIAMI, ARIZONA.

COMBINED LOCK AND LATCH.

Application filed October 15, 1923. Serial No. 668,639.

To all whom it may concern:
 Be it known that I, CHARLES W. RODDY, citizen of the United States, residing at Miami, in the county of Gila and State of Arizona, have invented certain new and useful Improvements in Combined Locks and Latches, of which the following is a specification.

This invention relates to locks and latches and has particular reference to what may be termed a cylinder-knob combined lock and latch, particularly adapted for use upon the doors of dwellings or the like.

The primary object of the invention is to provide a device of the above kind which may be cheaply and easily installed and manufactured, one that will be extremely durable and efficient in operation, and one by means of which, when the door is locked from one side of the latter, it may not be released from the other side thereof under any reasonable conditions.

Other objects will appear as the nature of the invention is better understood, and the same consists in the novel form, combination, and arrangement of parts hereinafter more fully described, shown in the accompanying drawings and claimed.

In the drawings, wherein like reference characters indicate corresponding parts throughout the several views:

Figure 1 is a substantially central longitudinal sectional view through the lock bolt, its casing and adjacent parts.

Figure 2 is a central sectional view through the lock as it appears applied to the door, the line of section being centrally and longitudinally of the knob and spindle, and the lock being shown in locked condition from the outside of the door.

Figure 3 is a view similar to Figure 2 with the lock in locked position from the inside of the door.

Figure 4 is a transverse sectional view taken substantially upon line 4-4 of Figure 2.

Figure 5 is a side elevational view of the key operated cam carrying cylinder.

Figure 6 is a transverse sectional view taken substantially upon the line 6-6 of Figure 3.

Figure 7 is an end elevational view of the inner cam cylinder.

Figure 8 is an inner end view of the operating means for the inner cam cylinder; and

Figure 9 is a side elevational view of one of the bolt locking pins.

Referring more in detail to the drawing, 5 indicates a portion of a door, to which the present invention is shown applied in Figures 2 and 3, and previous to installing the device, the door is provided with a transverse opening adjacent the free vertical end of the door and a longitudinal socket opening through said free vertical edge, the

transverse opening intersecting the inner end portion of said socket, and the opening and socket being preferably of circular cross section, whereby they can be formed in an expeditious manner by means of a wood auger

or drill. This constitutes the only modification of the door necessary and eliminates the objectionable and time consuming operation of morticing the doors as is necessary with many types of locks.

The present invention embodies a tube or sleeve 5 having its inner end suitably closed as at 6, and adapted to be snugly fitted within the above mentioned socket provided in the door, the outer end of the tube or sleeve

5 being provided with a rigid space plate 7 having openings 8 for reception of screws adapted to be threaded into the edge of the door for holding the tube 5 within the socket.

Snugly fitted for reciprocating movement within the sleeve 5 is a hollow locking bolt 9, having a reduced outer end 10 slidable in a suitable opening provided in the plate 7 and normally projected through said opening to engage in a striker plate fixed to the door jamb in a well known manner, by

means of a spring 11 that is arranged between the end wall 6 of the tube 5 and the inner end of the bolt 9; said spring being

preferably of helical form as shown and encircling an axially arranged pin 12 that is

suitably fixed to the closure 6 and slidably disposed in a central opening provided in the inner end of the bolt 9 as shown in Figure 1.

As shown clearly in Figures 2 and 3, a bearing ring or block is disposed within

each end of the transverse opening of the door 5 so that said bearing rings are disposed at opposite sides of the inner end portion of the tube 5. Transverse sockets are 5 provided in the sides of the inner end portions of the lock bolt 9, and normally register with transverse openings provided through the tube 5 and the bearing rings 13, locking pins 15 being arranged within the 10 openings of the bearing rings 13 and retracted out of the pockets 14 of the bolt 9 by means of springs 16 that are preferably of the helical compression type and which have their outer ends bearing upon heads 17 provided upon the outer ends of said pins 15, the inner ends of the springs 16 being in contact with shoulders provided by counter-boring the outer portions of the transverse openings in the bearing rings 13 as 20 shown.

The lock embodies a knob spindle composed of an inner section 18 having a cylindrical reduced inner end journalled in the inner bearing ring 13 and having an 25 axial socket of angular cross section opening through the inner end thereof. The knob spindle further includes an outer section 19 that has a reduced cylindrical central portion journalled within the outer 30 bearing ring 13 from which projects a further reduced inner end portion 20 of angular cross section that snugly fits within the socket of the spindle section 18 and which may be secured in said socket in the well 35 known manner by means of a set screw indicated in cross section at 21 in Figures 2 and 3.

The squared inner portion 20 of the outer 40 knob spindle section 19 passes through the open opposite side of the bolt 9 and has a shoulder block 22 secured thereon, the shoulders of which cooperate with shoulders on the interior of the bolt 9 as indicated at 23 in Figure 1 for causing retraction of the bolt 9 upon rotation of the knob spindle. The knob spindle and block 22 carried thereby are normally held and 45 yielding returned to a position wherein the bolt 9 is allowed to be projected by means of a spring 24 that is attached to the block 22 at its inner end and is arranged upon a pin 25 carried by a transverse partition 26 or the like provided interiorly of the bolt 9 near the outer end of the latter, the outer 50 end of the spring 25 bearing against the member 26 as shown clearly in Figure 1.

Sleeves 27 and 28 are respectively disposed with their inner ends against the outer sides of the bearing rings 13 and the outer 60 end of the spindle sections 19 and 18 are respectively secured within the inner ends of said sleeves 27 and 28 respectively by means of a transverse rivet 29 and the set screw 21, the inner ends of the sleeves 27 and 28 being journalled in central openings provided in

escutcheon plates 30 secured against opposite sides of the door with their openings coincident with the transverse opening in the door. Suitable knobs, preferably formed of pressed metal, are secured upon the outer end portions of the sleeves 27 and 28, the larger outer end portions of the knob central sections 18 and 19 fit snugly in the inner ends of the sleeves 27 and 28 and are provided with longitudinal peripheral 70 grooves, in which are slidably mounted operating rods 32 adapted to be forced inwardly for causing the locking pins 15 to enter the sockets 14 of the bolt 9, whereby retraction of the latter is prevented, the rod 80 32 being normally aligned with the pins 15 for this purpose. A plate 33 is secured against the outer ends of the knob spindle by means of a screw 34 or the like, and each of said plates 32 is provided with a plurality of resilient wings 35 each of which is secured to the outer end of one of the rods 32, whereby said rods are normally withdrawn or retracted from the bearing rings 13 so as to allow the locking pins 15 to automatically return to retracted bolt releasing position, and the rods 32 are of such length as to have their inner ends normally lie outwardly of the bearing rings 13 whereby said rods 32 will not interfere with the 90 free turning movement of the knob spindle, and whereby the bolt 9 may normally be readily retracted.

A cylinder 36 is rotatably disposed within the outer end of the sleeve 27, while a further cylinder 37 is arranged within the outer end of the sleeve 28, and said cylinders are both provided upon their inner ends with marginal inwardly projecting cam members 38 that are of annular form, 100 and disposed with their inner cam edges in contiguous relation with the outer ends of the rods 32. The cams 38 are so formed that when they are disposed in one position, both of the rods 32 associated therewith are allowed to retract for permitting the locking pins 15 to release from the bolt, and when in another position, to force said rods 32 inwardly and so retain the same for moving the locking pins 15 into the socket 115 14 of the bolt 9 and retaining the locking pins 15 thus disposed. This desired form is provided by making the cams of a two point type when only two locking pins and operating rods are provided at each side.

The cylinder 36 is retained within the sleeve 27 by means of the outer end wall of the adjacent knob 31 which abuts an outward flange 39 provided on the outer end of said sleeve 27, and said cylinder 36 is 125 provided with a central key receiving slot or opening 40 that is coincident with a key hole 41 provided centrally in the outer end wall of the adjacent knob 31. The cylinder 36 is provided with one or more transverse 130

openings 41 which intersect the opening 40 and within which are slidably disposed tumbler pins 43 that are provided with notches 44 as at 44 in sides of the same, the notches 44 being aligned with the opening 40 in one plane. Pins 45 are rigid with and project laterally from the opposite sides of the pins 43 and enter elongated grooves 46 provided at the latter sides of the tumbler pins 43 as shown in Figure 4, a spring 47 being arranged within each groove 46 and engaging the adjacent pins 45 so as to normally project the tumbler pin 43 thereof into suitable openings 48 provided in the outer ends of the sleeve 27. By means of this construction, the cylinder 36 is retained in such position as to hold the rods 32 inwardly projected with the locking pins 15 engaging in the socket 14 of the lock bolts 9, whereby rotation of the knob and spindle at the outside of the door is effectively prevented and retraction of the bolt 9 thereby rendered impossible by an unauthorized person not possessing a key of the proper form for releasing the tumbler pins 43. This key is of a well known general type adapted to be slid into the opening 40 through the key hole 41 and containing spaced projections for forcing the pins 43 out of the openings 48 by riding upon the shoulders that are arranged in the path thereof and that are formed by providing the notches 44. Obviously, the opening 40 is of such form as to accommodate a key in such manner that when the latter retracts the tumbler pins 43, said cylinder 36 may be freely rotated by said key for releasing the rod 32 and the locking pins 15 operated thereby, whereby the knob at the outside of the door and the knob spindle may then be readily rotated for operating the block 22 to retract the bolt 9 against the action of the springs 11 and 24.

The cylinder 37 is provided with a central socket 49 in its outer end and is formed with outwardly projecting ribs or lugs 50 at opposite sides of said socket 49. A special form of permanent key 51 has a central reduced shank portion slidably disposed through a central opening formed in the outer end wall of the inside knob 31 and is formed with an enlarged inner end portion forming a shoulder normally engaging said wall of the inner knob 31, whereby the outward movement of the key 51 is limited, and displacement of said key from the sleeve 28 is prevented. The key 51 is normally forced outwardly to released position by means of a spring 52 that has one end disposed within the socket 49 and has its other end bearing against the inner end of the key 51 as shown clearly in Figure 2. An enlarged head 53 is formed upon the outer end of the key 51, and the margin or periphery thereof is knurled or roughened to pro-

vide a handle by means of which the key 51 may be rotated. The inner end of the key 51 is formed with notches 54 adapted to cooperate with the lugs 50 of the cylinder 37, when the key 51 is forced inwardly so as to clutch said cylinder and key together, whereby the key 51 may be rotated at that time for causing rotation of the cylinders 37 to a position wherein the adjacent rods 32 are released for permitting release of the 75 cooperating locking pins 15 at the inner side of the device. On the other hand, the spring 52 normally forces the key 51 outwardly to unclutch the latter from the cylinder 37 so that when the cam 38 of said cylinder 37 is disposed to retain the rods 32 and pins 15 in bolt locking position within the socket 14 at the inner side of the bolt 9, rotation of the inner knob 31 and the knob spindle is effectively prevented for preventing retraction of the bolt 9 especially from the outside of the door, even though the outer locking pins 15 are released.

As the entire construction and operation of the invention has been dealt with in detail in the above description, it is believed that the same, as well as the advantages thereof will be understood and appreciated by those skilled in the art.

Minor changes may be made without departing from the spirit and scope of the invention as claimed.

What I claim as new is:

1. In a cylinder knob lock, a sliding lock bolt having retracting means including a knob spindle, and provided with sockets in opposite sides thereof, knob carrying sleeves secured to and enclosing the knob spindle, cylinders rotatable in the outer ends of said sleeve, normally released locking pins adapted to engage in the sockets of said lock bolt for preventing retraction of the latter, and means operatively connecting said locking pins and said cylinders whereby when the latter are rotated to one position, the locking pins are held in locking position and when moved in another position, said pins are allowed to move to released position.
2. In a cylinder knob lock, a sliding lock bolt having retracting means including a knob spindle, and provided with sockets in opposite sides thereof, knob carrying sleeves secured to and enclosing the knob spindle, cylinders rotatable in the outer ends of said sleeve, normally released locking pins adapted to engage in the sockets of said lock bolt for preventing retraction of the latter, means operatively connecting said locking pins and said cylinders whereby when the latter are rotated in one position the locking pins are held in locking position and when moved in another position, said pins are allowed to move to released position, one of said cylinders constituting the cylinder of a pin tumbler lock, the pins of which normally

engage the adjacent sleeve for preventing rotation of said cylinder relative to the last mentioned sleeve.

3. In a cylinder knob lock, a sliding lock bolt having retracting means including a knob spindle, and provided with sockets in opposite sides thereof, knob carrying sleeves secured to and enclosing the knob spindle, cylinders rotatable in the outer ends of said sleeve, normally released locking pins adapted to engage in the sockets of said lock bolt for preventing retraction of the latter, and means operatively connecting said locking pins and said cylinders whereby when the latter are rotated to one position, the locking pins are held in locking position and when moved in another position, said pins are allowed to move to released position, said lock bolt having a casing extending at right angles to the knob spindle, bearing rings arranged at opposite sides of said bolt casing, and in which the knob spindle is journaled, said locking pins being carried by said bearing rings.
- 25 4. In a cylinder knob lock, a sliding lock bolt having retracting means including a knob spindle, and provided with sockets in opposite sides thereof, knob carrying sleeves secured to and enclosing the knob spindle, cylinders rotatable in the outer ends of said sleeve, normally released locking pins adapted to engage in the sockets of said lock bolt for preventing retraction of the latter, means operatively connecting said locking pins and said cylinders whereby when the latter are rotated in one position, the locking pins are held in locking position and when moved in another position, said pins are allowed to move to released position, said lock bolt having a casing extending at right angles to the knob spindle, bearing rings arranged at opposite sides of said bolt casing and in which the knob spindle is journaled, said locking pins being carried by said bearing rings, the operative connection between the locking pins and the cylinders including circular cams rigid with and projecting inwardly from the inner ends of said cylinders.
- 50 5. In a cylinder knob lock, a sliding lock bolt having retracting means including a knob spindle and provided with sockets in opposite sides thereof, knob carrying sleeves secured to and enclosing the knob spindle, cylinders rotatable in the outer ends of said sleeve, normally released locking pins adapted to engage in the sockets of said lock bolt for preventing retraction of the latter, means operatively connecting said locking pins and said cylinders whereby when the latter are rotated in one position, the locking pins are held in locking position and when moved in another position, said pins are allowed to move to released position, said lock bolt having a casing extending at right angles to the knob spindle, bearing rings arranged at opposite sides of said bolt casing and in which the knob spindle is journaled, said locking pins being carried by said bearing rings, the operative connection between the locking pins and the cylinders including circular cams rigid with and projecting inwardly from the inner ends of said cylinders.

to the knob spindle, bearing rings arranged at opposite sides of said bolt casing and in which the knob spindle is journaled, said locking pins being carried by said bearing rings, the operative connection between the locking pins and the cylinders including circular cams rigid with and projecting inwardly from the inner ends of said cylinders, and normally outwardly retracted operating rods slidably mounted within the sleeves and movable inwardly by said cams for forcing the locking pins inwardly to locking position upon rotation of said cylinders.

6. In a cylinder knob lock, a sliding lock bolt having retracted means including a knob spindle and provided with sockets in opposite sides thereof, knob carrying sleeves secured to and enclosing the knob spindle, cylinders rotatable in the outer ends of said sleeve, normally released locking pins adapted to engage in the sockets of said lock bolt for preventing retraction of the latter, means operatively connecting said locking pins and said cylinders whereby when the latter are rotated in one position the locking pins are held in locking position and when moved in another position, said pins are allowed to move to released position, one of said cylinders constituting the cylinder of a pin tumbler lock, the pins of which normally engage the adjacent sleeve for preventing rotation of said cylinder relative to the last mentioned sleeve, the other cylinder having a clutch element formed upon the outer end thereof, and a permanent key mounted within the sleeve carrying said other cylinder and having a clutch element movable into engagement with the clutch element of said second named cylinder, whereby rotation of the key may be imparted to said last named cylinder.

7. In a cylinder knob lock, a sliding lock bolt having retracting means including a knob spindle and provided with sockets in opposite sides thereof, knob carrying sleeves secured to and enclosing the knob spindle, cylinders rotatable in the outer ends of said sleeve, normally released locking pins adapted to engage in the sockets of said lock bolt for preventing retraction of the latter, means operatively connecting said locking pins and said cylinders whereby when the latter are rotated in one position, the locking pins are held in locking position and when moved in another position, said pins are allowed to move to released position, said lock bolt having a casing extending at right angles to the knob spindle, bearing rings arranged at opposite sides of said bolt casing and in which the knob spindle is journaled, said locking pins being carried by said bearing rings, the operative connection between the locking pins and the cylinders including circular cams rigid with and projecting inwardly from the inner ends of said cylinders.

ders, said knob spindle comprising a pair of sections, one of which has a reduced inner end and the other of which has a reduced central portion journalled in the bearing 5 ring, said other spindle section having an inner end portion of angular cross section, the first named spindle section having a socket of angular cross section in which the

inner ends of said first mentioned spindle section is detachably secured, and the bolt retracting means embodying a shoulder slot secured upon the said inner end of the first named spindle section. 10

In testimony whereof I affix my signature.

CHARLES W. RODDY.
